(57) **CLAIM**

The ornamental design for wireless charger, as shown and described.

DESCRIPTION

Figure 1.1 is a front view of a first embodiment of a wireless charger showing my new design;

Figure 1.2 is a back view thereof;

Figure 1.3 is a left view thereof;

Figure 1.4 is a right view thereof;

Figure 1.5 is a top view thereof;

Figure 1.6 is a bottom view thereof;

Figure 1.7 is a perspective view thereof;

Figure 2.1 is a front view of a second embodiment of a wireless charger showing my new design;

Figure 2.2 is a back view thereof;

Figure 2.3 is a left view thereof;

Figure 2.4 is a right view thereof;

Figure 2.5 is a top view thereof;

Figure 2.6 is a bottom view thereof; and

Figure 2.7 is a perspective view thereof.

The broken lines depict portions of the wireless charger that form no part of the claimed design.

(Continued)

The wireless charger having two charging positions is applicable for smartphones, smartwatches and some related smart products.

1 Claim, 14 Drawing Sheets
